COMBINED PLAYGROUND CLIMBER AND SLIDE REPRESENTING A TEEPEE

Ronald W. Zick, Coldwater, Mich., assignor to
Game Time, Inc.

Filed Feb. 25, 1974, Ser. No. 445,618

Term of patent 14 years

Int. Cl. D21—03

U.S. Cl. D34—5 E

FIG. 1

FIG. 2

FIG. 3

FIG. 4

FIG. 5

FIG. 1 is a side elevational view of a combined playground climber and slide representing a teepee in accord with my new design;

FIG. 2 is an elevational view of the opposite side of the design with respect to FIG. 1;

FIG. 3 is a side elevational view as taken from the left of FIG. 1;

FIG. 4 is a side elevational view as taken from the left of FIG. 2; and

FIG. 5 is a top plan view of my new design.

I claim:

The ornamental design for a combined playground climber and slide representing a teepee, substantially as shown and described.
